WINDOW SASH CONSTRUCTION

Edward F. Chaffee, Syracuse, N. Y., assignor to
The O. M. Edwards Company, Inc., Syracuse,
N. Y., a corporation of New York

Application October 28, 1937, Serial No. 171,528

3 Claims. (Cl. 189—78)

This invention relates to window sash constructions, and has for its object a window construction, which consists merely of a frame suitably recessed or channeled for receiving a glass pane and a glazing strip of resilient compressible material, which is readily applied and also intentionally removable but held from unintentional displacement.

The invention consists in the novel features and in the combinations and constructions hereinafter set forth and claimed.

In describing this invention, reference is had to the accompanying drawing in which like characters designate corresponding parts in all the views.

Figure 1 is an isometric view of the corner portion of a sash embodying this invention.

Figure 2 is a transverse fragmentary sectional view through the sash illustrating a slightly different form of the invention from that shown in Figure 1.

Figure 3 is a fragmentary isometric view of the glazing strip before being applied to the sash.

Figure 4 is a view similar to Figure 2 of another slightly modified construction.

In modern window sashes, such as are used and coming more and more into use, in railway cars and other vehicles, it is desired that the glass pane be resiliently mounted in the sash frame and also be readily mountable in or readily replaceable, when broken. The glass pane is mounted against a resilient backing and held in position by resilient compressible glazing strips which are capable of being placed in position or being pressed into position an inch or so at a time and also are capable of being quickly pulled out of position for the purpose of replacing a broken pane. Glazing strips of this type have heretofore been firmly interlocked with the sash frame or some other part associated therewith. The interlocking requires skill or care on the part of the workman.

One of the objects of this invention is a window construction embodying a resilient compressible glazing strip in which no interlocking of the strip and the window sash or associated parts against edgewise displacement is employed but at the same time the strip is held from unintentional outward shifting or displacement.

The feature of the invention is a compressible retaining or glazing strip provided with means by which a displacing movement out of the glazing strip groove or channel wedges, without interlocking means, the glazing strip more firmly

in the glazing strip groove or channel but permits the intentional displacing upon sufficient pulling force being applied, such pulling force, when once started, tending to stretch the glazing strip, which is elastic, and hence tending to release the wedging means.

The window sashes are usually formed with rounding corners, and the glazing strip has a great tendency to loop out of the glazing strip groove at the rounding corners.

In Figure 1, 1 designates a sash frame formed up of sheet metal to have one side higher than the other, the higher side being formed with a rabbet 2 for receiving the margin of the glass pane 3 and an interposed resilient backing strip 4. The frame is also formed up to have a retaining or glazing strip groove or channel 5 located beyond the bottom of the rabbet 2 and the edge of the glass pane, this groove having parallel opposing side walls. Because the side at which the glazing strip groove is located, is lower than the other side, the glass pane can be quickly placed substantially flatwise into the rabbet 2 and then the glazing strip, to be described, applied.

25 The backing strip 4 in Figure 1 is shown as angular or L-shaped in cross section with one flange thereof backing against the inner face of the higher wall of the sash frame and the other flange thereof seating on the bottom of the rabbet 2. The glass pane presses against the backing strip and may also press at its edge against the portion of the backing strip on the bottom of the rabbet.

35 6 designates the retaining or glazing strip, this being of a resilient compressible and somewhat elastic material, as some form of rubber. It is usually formed by an extruding operation. It includes a base portion 7 and a head portion 8, the base portion 7 being rectangular in cross section to fit in between the parallel sides of the groove 5 and owing to the parallel sides of the rectangular formation is readily compressed into the groove without the exercise of much care or skill. It is formed on at least one side thereof with one or more inclined projections inclined toward the entrance of the groove 5 in order to flatten without resistance toward the body of the base 7 when the base 7 is being compressed into the groove 5 and to spread outwardly or 45 straighten to in effect increase the widthwise direction of the base 7, and hence wedge the base in the groove, when the glazing strip is subject to any force tending to shift it or cause it to creep out of the groove 5.

55 9 designates the projections, which are in the

form of barbs in cross section. In Figure 1, they are shown as engaging the inner wall of the groove 5. The head 8 is provided with a shoulder at 10 thrusting on the edge of the lower wall of the sash frame. The strip before being applied is of the form shown in Figure 3, and hence distorts and is under tension, when placed in the sash frame, as shown in Figure 1. The backing strip 4 is first applied to the rabbet in the sash frame and may be secured thereto as by an adhesive. The glass pane is then placed against the backing, and then the glazing strip pressed, starting at one end or at any point and inching the base portion thereof into the groove 5. During this operation, the barbs 9 fold down against the body of the base portion, permitting the base portion to slip comparatively easily between the parallel sides of the groove 5. During this pressing or inching operation, the base portion is also compressed and then when the compression is released, the base portion reacts against the parallel side walls of the groove 5 with sufficient friction to hold it from displacement. However, if the strip is subject to a force tending to displace the base portion out of the groove, the barbs tend to straighten and more firmly wedge the glazing strip in the groove. In removing the glazing strip, it or one end of it is started out of the groove, and then a pulling force applied tending to stretch the glazing strip, the pulling or stretching tending to contract the glazing strip in a widthwise direction, and hence releases its frictional wedging contact with the walls of the groove 5. Thus, the glazing strip can be readily applied and removed without providing any construction or means for interlocking with the sash frame.

In Figure 2, the sash frame is shown in the cross sectional form of a rectangular channel, with one side higher than the other, and the backing strip 11 is shown as having a base portion 12 fitting the channel beyond the edge of the glass pane 13 but being of less width than the channel, so that one face thereof is opposed to the lower wall 14 of the sash frame, providing the glazing strip groove 15. However, both sides of the groove are parallel, and the base portion of the glazing strip formed with barbs 16 co-acting with the wall of the groove formed by the base 12 of the backing strip 11.

In Figure 4, the barbs 16 are shown as provided on one wall of the glazing strip groove and specifically on the base portion 12 of the backing strip 11. Also, in Figure 4, barbs 17 are shown on the base portion of the glazing strip and co-acting with the inner face of the side of the sash frame forming the wall of less height of the sash frame.

In any form of the invention, the barbs compress, when the strip is being compressed into the glazing strip groove and tend to expand into a straight line or exert a greater outward pressure upon shifting movement of the glazing strip out of the glazing strip groove, and this wedging action or frictional engagement is relieved to a large extent, when the glazing strip is being removed by pulling on it. When the sash is in normal use, there are no conditions tending to apply the stretching force to the glazing strip, or, in other words, the tensioning force must be intentionally applied.

In the constructions shown in Figures 1 and 2, the frame 1 and the backing strip 4 or 11 constitute a unit, and this unit is provided with a groove having sides parallel to the plane of the

glass for receiving the base portion of a retaining or glazing strip, which base portion is provided with barbs to restrain the working of the retaining or glazing strip or the base thereof out of the groove. In the form shown in Figure 1, this groove is formed wholly in the frame itself. In the form shown in Figure 2, the groove is formed between the parts of the unit consisting of the backing strip and the frame. The feature of both is the barbs or their equivalent tending to expand and frictionally hold the retaining or glazing strip from working out of the groove.

The barbs also facilitate the placing of the glazing strip into the glazing strip groove, as they fold or flatten against the body of the strip when the strip is being pressed into the groove. The strips, which are formed by an extruding process, vary in width slightly and also the grooves vary. The barbs compensate for variations in the strips and in the grooves.

What I claim is:

1. In a window sash construction comprising a frame provided with means for forming a glass receiving rabbet open at one side and arranged with a groove located beyond the edge of the glass pane and out of the plane thereof, the groove having substantially parallel smooth sides, and a glazing strip of elastic resilient compressible material having a base portion formed with parallel sides compressible in the groove, and a head portion of greater width than the base portion and normally projecting beyond the plane of the side of the base portion toward the glass pane and pressing against the glass pane, whereby the head portion is under compression in a direction transversely of the base portion when compressed against the glass pane, and hence tends to pull the base portion out of the groove, the combination of said sash construction having means limiting the lateral movement of the head portion under the transverse compression force, and of the base portion of the glazing strip having means tending to expand in a widthwise direction against the walls of the groove and to grip the same under the transverse compression action of the glass pane on the head portion and tighten the base portion in the groove against outward displacement.

2. In a window sash construction comprising a frame provided with means for forming a glass receiving rabbet open at one side and arranged with a groove located beyond the edge of the glass pane and out of the plane thereof, the groove having substantially parallel smooth sides, and a glazing strip of elastic resilient compressible material having a base portion formed with parallel sides compressible in the groove, and a head portion of greater width than the base portion and normally projecting beyond the plane of the side of the base portion toward the glass pane and pressing against the glass pane, whereby the head portion is under compression in a direction transversely of the base portion when compressed against the glass pane, and hence tends to pull the base portion out of the groove, the combination of said sash construction having a shoulder at the edge of the outer side wall of the groove on which the head portion presses, said shoulder limiting lateral movement of the head portion under the transverse compression force, and of said base portion having means tending to expand in a widthwise direction against the side walls of the groove and to grip the same under the transverse compression action of the glass pane on the head portion and

tighten the base portion in the groove against outward displacement.

3. In a window sash construction comprising a frame provided with means for forming a glass receiving rabbet open at one side and arranged with a groove located beyond the edge of the glass pane and out of the plane thereof, and a glazing strip of elastic, resilient, compressible material having a base portion compressible in the groove, and a head portion of greater width than the base portion and normally projecting beyond the plane of the side of the base portion toward the glass pane and pressing against the glass pane, whereby the head portion is under compression in a direction transversely of

the base portion, when compressed against the glass pane, and hence tends to pull the base portion out of the groove; the combination of said sash construction having means limiting the lateral movement of the head portion under the transverse compressible force and of the groove having substantially parallel side walls parallel to the plane of the glass pane, and of the base portion of the glazing strip having means to expand in a widthwise direction against the parallel walls of the groove to grip the same under the transverse compression action of the glass pane on the head portion, and tighten the base portion in the groove.

EDWARD F. CHAFFEE.
